FIRE EXTINGUISHER

Filed Dec. 21, 1928

UNITED STATES PATENT OFFICE

NINO BELLOCCHIO, OF NEW YORK, N. Y.

FIRE EXTINGUISHER

Application filed December 21, 1928. Serial No. 327,540.

This invention relates generally to fire extinguishers and has more particular reference to a manual operable fire extinguisher.

The invention has for an object the provision of a device of the class mentioned which is of simple durable construction, desirable in use and efficient in action, and which can be manufactured and sold at a reasonable cost.

10 The invention proposes the use of a bottle containing a solution of sodium bicarbonate and having a neck engaged by a stopper in which a plunger is slidably mounted. This plunger is provided with a head, and the opposite end acts against a disc resting upon a container filled with citric acid. A soft metal cylinder is attached upon the stopper and has inturned edges coacting with out turned edges of the citric acid container for 15 normally holding the container in position. Depression of the plunger causes the soft metal to give and causes the container with the citric acid to drop. A discharge tube is connected within the bottle and extends to 20 the outer side thereof thru which extinguishing solution may pass.

The present application showing a further development of the invention disclosed in my pending application, filed July 14, 1928, 25 Serial No. 292,778.

For further comprehension of the invention, and of the objects and advantages thereof, reference will be had to the following description and accompanying drawings, 30 and to the appended claims in which the various novel features of the invention are more particularly set forth.

In the accompanying drawing forming a material part of this disclosure:—

40 Fig. 1 is a plan view of a device constructed according to this invention.

Fig. 2 is a central vertical sectional view thereof.

Fig. 3 is a horizontal sectional view, taken 45 on the line 3—3 of Fig. 2.

Fig. 4 is a fragmentary sectional view of the same device constructed according to modified form.

Fig. 5 is an enlarged sectional view of a 50 portion of this device.

The reference numeral 10 indicates generally a bottle of any design or construction, preferably made of metal and having a neck 11 provided with threads 12. A stopper 13 threadedly engages within the neck and has 55 an enlarged head 14 for the manipulation thereof.

The stopper 13 is provided with a central aperture 15 in which a plunger 16 is slidably mounted. This plunger has an enlarged 60 head 17 and a pin 18 near its bottom end. This pin engages in a slot 19 formed in the stopper for preventing complete outward displacement of the plunger. A soft metal cylinder 20 is attached on the stopper and is 65 formed with inturned bottom edges 21 of soft metal. A container 22 holding citric acid 23, is formed with out turned top edges 24 coacting with the inturned edges 21 so as to normally maintain a stationary position. A 70 disc 25 rests on the top of the container 23 for closing the container, and the bottom edge of the plunger 15 rests upon this disc.

A solution of sodium bicarbonate 26 is contained in the bottle 10. A tube 27 contained 75 within the bottle 10 extends from the bottom thereof out of the top. The extension 27' of this tube is preferably flexible and has a nozzle 28 at its free end. A flange 29 is attached on the bottle and on the tube on the point 80 where the tube extends out of the bottle. Another flange 30 is connected on the inner end of the tube and onto the bottle for holding this end of the tube against displacement. A plurality of apertures 31 are formed in the 85 tube near the bottom thereof for providing a passage of the solution 26 thru the tube.

In the modified form of the device illustrated in Fig. 4, a bottle 10^a has been shown with a neck 11^a and a plug 13^a threadedly 90 engages in the neck for closing the neck. A tube 27 is arranged in conjunction with this bottle as previously described in reference to the bottle 10. This bottle is provided with a top bent tube 32 communicating with an 95 auxiliary container 33 having a neck 11' in which a stopper 13 engages. This stopper is provided with a plunger 15 and with the citric acid container 22 as before described relative to the bottle 10. A connection 34 100

holds the lower portions of the bottle 10^a and the auxiliary container 33 in spaced conditions. The bottle 10^a is filled with water 35 and the auxiliary container 33 holds a solution of sodium bicarbonate 36.

5 In operation of the devices, the plunger 15 is manually depressed by striking the head 17. This causes the disc 25 to descend and straightens out the inturned edges 21 of the 10 soft metal cylinder 20. The container 22 then falls and the citric acid within the container mixes with the solution of sodium bicarbonate for liberating gases and forcing the contents of the bottles from the discharging tube 27.

15 The auxiliary container 33 shown in Fig. 4 serves as a handle for holding the device besides performing its function of holding the solution of sodium bicarbonate.

20 While I have shown and described the preferred embodiment of my invention, it is to be understood that I do not limit myself to the precise construction herein disclosed and the right is reserved to all changes and modifications coming within the scope of the invention as defined in the appended claims.

25 Having thus described my invention, what I claim as new, and desire to secure by United States Letters Patent is:—

30 1. In a fire extinguisher, a bottle for holding a solution of bicarbonate of soda, a stopper in the bottle, a container for holding citric acid suspended from the stopper, by reason of having out turned top edges engaging upon inturned bottom edges of a soft metal cylinder attached on the stopper, and a plunger mounted in the stopper, and arranged for detaching the container from the stopper upon downward motion thereof, a tube extending from the interior to the exterior of the bottle and arranged for discharging the contents of the same.

35 2. In a fire extinguisher, a bottle for holding a solution of bicarbonate of soda, a stopper in the bottle, a container for holding citric acid suspended from the stopper, a soft metal member attached on the stopper and having inturned edges engaging out turned edges projecting from the container and constituting the means for suspending the container from the stopper, and a plunger mounted in the stopper, and arranged for detaching the container from the stopper upon downward motion thereof, a tube extending from the interior to the exterior of the bottle and arranged for discharging the contents of the same.

40 3. In a fire extinguisher, a bottle for holding a solution of bicarbonate of soda, a stopper in the bottle, a container for holding citric acid suspended from the stopper, a soft metal member attached on the stopper and having inturned edges engaging out turned edges projecting from the container and constituting the means for suspending

the container from the stopper, and a plunger mounted in the stopper, a disc supported on the top of the container and beneath said plunger so that upon downward motion of the plunger said disc will press against the out turned edges of the container thereby urging the soft metal of the inturned edges of the stopper member outwards and thus causing the container to become detached from the stopper, a tube extending from the interior to the exterior of the bottle and arranged for discharging the contents of the same.

45 In testimony whereof I have affixed my signature.

NINO BELLOCCHIO.
